(57) **CLAIM**

The ornamental design of an adjustable template for measuring and replicating angles, as shown and described.

DESCRIPTION

FIG. 1 is a perspective view of the adjustable template for measuring and replicating angles

FIG. 2 is a top plan view of the adjustable template;

FIG. 3 is a bottom plan view of the adjustable template;

FIG. 4 is a left side view of the adjustable template;

FIG. 5 is a right side view of the adjustable template;

FIG. 6 is an end view of the adjustable template; and,

FIG. 7 is an end view of the adjustable template from the opposite direction as shown in FIG. 6.

1 Claim, 4 Drawing Sheets

FIG. 2

FIG. 3

FIG. 4

FIG. 5

FIG. 6

FIG. 7
